UNITED STATES PATENT OFFICE.

FENTON FREDERICK STRATTON, OF EAST CROYDON, ENGLAND.

CARBURETOR FOR INTERNAL-COMBUSTION ENGINES.

1,403,987.

Specification of Letters Patent. Patented Jan. 17, 1922.

Application filed March 18, 1918. Serial No. 223,212.

To all whom it may concern:

Be it known that I, FENTON FREDERICK STRATTON, a subject of the King of Great Britain and Ireland, and a resident of Oak 5 Lodge, Park Hill Road, East Croydon, Surrey, England, have invented new and useful Improvements in Carburetors for Internal-Combustion Engines, of which the following is the specification.

10 The objects of this invention are to provide better means for feeding the correct relative proportions of liquid fuel and air to the engine, and to better control the supply of mixture to the engine under all conditions 15 of running.

In this invention I provide an automatic valve similar to that described in my prior specifications Serial Nos. 117,095 and 184, 952, adapted to move vertically upward in 20 the carburetor when operated by the suction of the engine and to move downwardly in the carburetor by the action of gravity assisted or not by a spring, the said automatic valve in rising being adapted to open ports 25 formed in the wall of the carburetor to admit air; there may be one port for each liquid fuel jet brought into operation.

According to my invention I provide in 30 combination with the said valve, members constructed as hereafter described which not only operate as caps, that is to say, to close over the jet or nozzle until its corresponding air port has been opened by the automatic valve, but also to a certain extent as choke 35 tubes for each said jet. I suspend or support the combined cap and choke tube from a lug or the like secured to or integrally formed with the said valve in such manner that while the cap serves on rising to bring the 40 jet into operation, the choke tube integrally formed with the cap provides a progressively increasing area for the passage of air to correspond with the rise of the valve.

In forming the choke tube integrally with 45 the cap I provide one or more longitudinal slots in the side of the cap preferably on opposite sides of the cap, and preferably so arranged one a little higher than the other that air shall not only pass through the 50 choke tube to sweep the liquid fuel issuing from the end of the jets through the said slots, but also that air passing upwardly through the body of the carburetor when the port of that jet is fully open shall deflect 55 through the lower of the said slots to sweep

across the top of the jet and through the higher of the two said slots.

I provide on the base plate of the carburetor of the kind I have described in my said prior specifications, an annular centre 60 or ring projecting above, but formed integrally with the said base plate, which ring is adapted to fit and hold centrally the choke tube of the central pilot jet, and I form through the said annulus small holes for 65 the passage of air from the outer annular chamber to the said choke tube.

The above described construction is applicable to a carburetor in which one liquid fuel only is employed, petrol for example, or 70 one in which two liquid fuels are employed with two float chambers, petrol and paraffin for example, in which the petrol is supplied to the pilot jet only, and paraffin to the main jets only, and it is for use with two 75 liquid fuels that the invention is preferably employed, and it is as adapted for such use that the invention is shown in the accompanying drawings.

Fig. 1 is a sectional elevation through 80 the centre of the improved carburetor in the plane of the jets. In the example of the invention shown, only two jets are employed for the heavier liquid fuel in addition to the central jet used for starting purposes 85 and employing a lighter liquid fuel such as petrol or the like.

Fig. 2 is a sectional plan of the improved carburetor.

Fig. 3 is a vertical section of the base 90 plate.

Fig. 4 is a plan of same.

Fig. 5 is a sectional elevation of the jet chamber and valve cylinder showing two 95 of the air ports therein.

Fig. 6 is a sectional elevation of choke tube of the pilot or starting jet.

Figs. 7 and 8 are sectional elevation and elevation respectively of the new construction of cap which also acts partly as a choke 100 tube.

A is the central cylindrical casing containing the jet chamber having integrally formed therewith the second cylinder B of larger diameter. C is a sliding piston of 105 two diameters, the larger of which is adapted to slide or reciprocate loosely within the cylinder B, the inner or smaller diameter being formed as a hollow sleeve or extension C¹. The smaller diameter of the piston 110

valve C¹ is adapted to very loosely fit and slide within the smaller diameter of the central cylindrical jet chamber A. The piston valve C is open to the suction of the engine 5 on its upper face, and the lower surface of the said larger diameter of the valve is subject to the same pressure as obtains in the main or central chamber A of the carburetor. Air ports D are provided in the cylindrical 10 wall of the jet chamber A which are opened by the rising or lifting of the automatic piston valve C. In the specification Serial No. 184,952, these air ports are arranged in stepped relation in order that they shall be 15 opened successively and progressively as the valve rises. In the construction or example of the invention shown, there being only two main jets provided, these air ports D are arranged in the cylindrical wall of the chamber A at the same level.

E is the pilot jet for lighter liquid fuel enclosed within the choke tube F. The choke tube F is provided at the upper end with a central portion of reduced diameter 25 F¹ which permanently throttles, owing to this reduction in diameter, the air supply passing through the tube F. The air supply is fed to the tube F from the chamber A through the four radial channels F² shown 30 dotted in plan, Figs. 2 and 4. These are bored horizontally through the annular centre or ring G¹ projecting above but formed integrally with the base plate G, the tube F fitting within a central recess 35 within the said ring G¹, but not covering the said channels F², so that air may pass by the said radial channels F² to form the starting mixture by means of the lighter liquid fuel from the jet E before sufficient 40 suction or vacuum effect is produced by the engine to raise the automatic valve C.

H and I are the two main jets for the supply, in the example shown, of the heavier liquid fuel such as paraffin. These are 45 screwed into bifurcated passages H¹, I¹, formed in the base plate G and connected to the channel or passage J¹ communicating directly with the float chamber J of ordinary construction supplied with a heavier liquid fuel such as paraffin. The central 50 jet F is screwed into the end of the channel F⁴ (see Figs. 2, 3 and 4) which is in communication with the float feed chamber K, containing a supply of the lighter liquid fuel such as petrol, shown with the cap or 55 cover of the chamber removed. The cap or cover L which is centrally fitted or suspended over the main jet H is supported or suspended from the automatic valve C as 60 shown, the cap or cover being secured in such a manner that it may be adjusted as to the relative height with relation to the said jet as the valve rises by means of the pin holes L¹, the securing pin L⁵ being removable in order to fit in one of the holes

L¹. This provides for adjustment of the cap relatively to the valve from which it is suspended with relation to the jet H. The cap M is similarly fitted over the other jet I for heavier liquid fuel. The caps L and 70 M are each formed with a bell mouth L² M² respectively at the lower end, see Figs. 7 and 8; they are also provided with longitudinal slots indicated by the letters L³ L⁴ in Fig. 7, and by M³ M⁴ in Fig. 8. In each 75 cap one of the slots is placed at a higher level than the other.

Referring to Fig. 1, the base plate G is formed with an annular shoulder on its lower surface on which fits the flanged casting N provided at its centre with a screwed edge upon which the union nut O is secured. The nut O carries the elbow connection P by which heated air is conveyed to the carburetor through the ports Q R S in the base 85 plate G.

The throttle valve shown is of ordinary construction.

The carburetor operates as follows:—

When the engine is started and the suction 90 of the engine produces a negative pressure in the carburetor, the automatic valve is closed, air is drawn through the pipe P and the ports Q R S into the annular chamber T, and thence through the radial channels 95 F² to the choke tube F. Liquid fuel is supplied from the jet E and the starting mixture is conveyed by the reduced channel F¹ to the engine. When the engine has gathered speed sufficiently and the vacuum effect 100 increases, the valve C rises opening the air ports D. Simultaneously the caps L, M, in rising permit the passage of air longitudinally up the cap to a certain extent and fuel is fed from the jets H, I. As the valve rises 105 farther and lifts the caps farther relatively to the jets more air passes through each cap acting as a choke tube. The air and liquid fuel issuing from the jets passes upwardly and outwardly through the slots L³, L⁴, and 110 M³, M⁴. At the same time the valve rising farther and having attained approximately its maximum lift the air ports D are fully opened and the air in passing through the chamber A tends also to sweep across from 115 the lower slot L⁴ to the upper slot L³ in the one cap and the lower slot M⁴ to the upper slot M³ in the upper cap and to sweep there- 120 with the liquid fuel issuing from each of the jets H and I, to form mixture which passes outwardly by the throttle at the upper end of the carburetor to the engine.

It will be understood that the flow of petrol from the nozzle E ceases or nearly ceases when the lighter fuel feeding nozzles 125 come into play since when the air ports D are opened by the lengthening of the valve, air is so freely admitted to the inside of the carburetor that the suction practically ceases upon the jet E, this being due to a great 130

extent to the contracted area in the channel in the top end F'.

What I do claim as my invention and desire to secure by Letters Patent is:—

- 5 In a carburetor, a casing provided with an air intake port, a plurality of jets, a piston reciprocable in the casing and operated by the engine suction, tubular caps for the jets carried by the piston, each of said caps
  - 10 being constructed and arranged to slide over one of the jets, the caps being adapted to receive air at their lower ends, and each cap being closed at its upper end and having a pair of air ports intermediate the ends
- thereof, said air ports extending through the 15 side wall of the cap at points one above the other and at opposite sides of the cap, whereby air is permitted to flow from the exterior of the caps through the lower of said side air ports of the caps across the top 20 of the jet and out through the higher of the two air ports, substantially as and for the purpose set forth.

FENTON FREDERICK STRATTON.
